UNIVERSAL TIME INDICATING CLOCK

Thomas L. Robertson, Longview, Wash.

Application April 24, 1936, Serial No. 76,275

1 Claim. (Cl. 58—43)

This invention appertains to new and useful improvements in the general art of horology and more particularly to a novel world time indicating clock mechanism.

5 The principal object of the present invention is to provide a clock mechanism including a rotary dial having indicia thereon representing time intervals, and a stationary dial carrying geographical names mounted in proximity to the 10 rotary dial.

Another important object of the invention is to provide a simply constructed world time telling clock structure which will be of considerable assistance to persons having long range short 15 wave radio receivers.

Other important objects and advantages of the invention will become apparent to the reader of the following specification.

In the drawings:—

20 Figure 1 represents a front elevational view of the mechanism.

Figure 2 is a fragmentary side elevational view with the main portion of the structure in vertical section.

25 Referring to the drawings wherein like numerals designate like parts, it can be seen that numeral 5 represents the clock back and which on its front side has a plurality of small clips 6 secured thereto for engaging against the roll 7 on the inner edge portion of the annular rim 8. This rim is rotatable in the clips 6 to permit adjustment of the annular dial 9 with respect to the rotary dial 10. The dial 10 is situated in conjunction with the pointer 11 and 30 has the gear train 12 driving the same.

35 The dial 10 rotates in a clock-wise direction at a speed of one revolution in twenty-four hours, the same being carried by the gear mechanism 12. The dial 10 is marked by having a 40 line drawn diametrically therethrough the one end portion of which is marked "Midnight" while the other end portion is marked "Noon". Each half of the dial is divided into twelve equal parts which represent the hours from one to twelve 45 A. M. and one to twelve P. M. and are so marked in a counter-clock-wise manner. Each hour is then calibrated into five minute periods and the fifteen, thirty and forty-five minute periods are so marked. The shaded portion of the dial 10 50 from six P. M. to midnight and from midnight to six A. M. is so colored to represent the dark part of the twenty-four hour period.

The annular dial 9 is secured against the glass

pane 13 and the glass pane 13 is held in place against the inturned flange 14 of the rim 8 by the spring members 15.

The rim 8 does not have any motion except that it can be rotated until the geographical location on dial 9 corresponding to the place where the clock is located coincides with the hour (indicated on dial 10) representing local time at the place where the clock is situated. This rim 8 has its dial 9 marked as follows: 10

The same is divided into twenty-four equal portions, each portion representing fifteen degrees of longitude for one hour of time, each division line being numbered on its outside end with its respective degrees of longitude in the 15 same manner in which degrees of longitude are marked on a world map. Each portion of the dial 9 is further divided by a line of half hour marks. Running laterally and continuously around the center of this dial is a mark or line 20 which is lettered "Equator". Around this rim 8 and close to the degree or divisional line which marks the time zones are placed the names of various countries of the world. These names are placed on the inside of the Equator line if 25 they are located above the Equator and on the outside of the Equator line if they are located below the Equator. Names of countries on the half hour standard are placed near the half hour mark. The Greenwich Meridian and the date 30 line are also shown in their respective places.

While the foregoing specification sets forth the invention in specific terms, it is to be understood that numerous changes in the shape, size and material may be resorted to without departing from the spirit and scope of the invention as claimed hereinafter. 35

Having described the invention what is claimed is:—

A clock structure comprising a back, guides 40 carried by the back, an annulus having its inner edge rotatably supported by said guides, a clock mechanism mounted on the back within the confines of the annulus, a rotary dial carried by the clock mechanism and having indicia thereon 45 representing time intervals, and a second dial of annular construction secured to the outer edge of the annulus, said second dial having its inner edge terminating at approximately the periphery of the rotary dial and having indicia 50 thereon indicating different geographical places.

THOMAS L. ROBERTSON.
